8 Claims. (Cl. 139—1)

This invention relates to the art of reweaving worn and damaged fabric.

An object of this invention is to provide a method of reweaving or reconstructing the weave in a worn or otherwise damaged area of a fabric.

Another object of this invention is to provide a method of reweaving or reconstructing the weave of a fabric in or through a worn or damaged area, so that the reweaving or reconstructing cannot be detected on the face of the fabric.

A further object of this invention is to provide a method of reweaving or reconstructing a fabric which will not only replace the fabric strands or yarn, but will also provide a construction having the strength of the original fabric and which will not pull out.

A further object of this invention is to provide a method of reweaving a fabric which is simple in procedure, so that any person unskilled in the art can easily follow the method and produce a satisfactory reconstruction or reweaving of the fabric.

A further object of this invention is to provide an improved method of reweaving or reconstructing a fabric which includes the initial step of reestablishing the warp threads or yarn across the damaged spot or area, with the opposite ends of the inserted warp threads woven into the main fabric on opposite sides of the damaged spot or area, and then reestablishing the filler or weft threads or yarn with the opposite ends of the latter threads or yarn woven into the main fabric on opposite sides of the damaged spot or area.

A further object of this invention is to provide an improved method whereby like warp and filler or weft threads or yarn may be obtained from the main fabric or garment without damaging the fabric or garment, so that these removed threads taken from a remote part of the main fabric or garment may be used in reconstructing the fabric in the damaged area.

A further object of this invention is to provide an improved method of reconstructing a damaged spot or area in a fabric, wherein the reconstructed part is actually reweoven by a weave identical with the weave of the fabric, so that there will be no appearance of a repaired area.

A further object of this invention is to provide an improved method of reweaving a worn area in a fabric which includes cutting each worn thread or strand, tying an end of a new thread onto an end of each worn thread, pulling each worn thread from the fabric and also reweaving the new thread in the space occupied by the worn thread, and finally reweaving the opposite ends of the inserted threads into the fabric.

In the carrying out of this invention, it is necessary to follow the correct steps for reweaving, i. e., anchoring each new thread so perfect-

ly and following the correct principle of leverage, in such a manner as to restore the full strength of the damaged area, and when necessary by carefully extending the threads and anchoring points, actually increase the wearing resistance of the reweoven area in the damaged garment. Instead of just pulling threads through the fabric in any haphazard manner, this invention contemplates following a planned procedure, i. e., of entering, anchoring, progressing and interlocking, and certain very definite and necessary rules which are necessary because reweaving must accomplish two things: First, to restore the original appearance of the fabric, and second, to restore the strength and wearing quality of the fabric. Unless the above two points are accomplished, the result is not genuine reweaving. In the reweaving of a damaged fabric, where the damage consists of strands which are worn thin or is in the form of a hole in the fabric, the first step is to determine the exact weave of that particular fabric. In some fabrics, the cloth is loosely woven, and the threads are thick and when this condition is present, the weave can often be easily and quickly determined by a visual inspection of the fabric when the operator understands and follows the rules for reweaving.

One of the most important steps in connection with the reweaving of the fabric is the initial determination of the "Weave Formula" of the particular fabric. The term "formula" is herein defined as the specific weave, over and under, of the filler threads with respect to the warp threads. After a person has had some experience in the reweaving of fabrics, he will be able to determine by a visual inspection the correct formula of certain of the fabrics. The formula is initially determined by a careful examination of the damaged fabric. Where the fabric threads are fairly thick, this examination may be made by a visual inspection which may include pulling or raveling a number of warp threads and at the same time jotting down on a piece of paper the progression of the warp threads over and under the filler threads; as an example, the progression is noted as one over, one under in a tabby weave and is placed on the formula chart as follows:

1
1

Where a fabric has a design woven thereinto, a sufficient number of warp threads are pulled out until the repeat of the weave is obtained. The correct weaving of the filler threads is then jotted down on the chart in the same manner as the warp threads. This chart then serves as the guide during the reweaving operation to be hereinafter described.

In the event the threads of the fabric are fairly

thin, it may be necessary in the determination of the weave formula to inspect the fabric under a magnifying glass and remove the warp and filler threads under the high-powered glass. In certain fabrics the threads are of a loose twist, that is, the fibers are not tightly twisted together, so that the fibers of one thread intermingle with the fibers of an adjacent thread thereby making it difficult, if not impossible, to pull the threads apart, and at the same time, determine the weave formula thereof. In a case of this kind, the fabric is dipped in molten wax. The hardened wax will firmly bind the fibers of each thread together, so that the warp and filler threads may be separated without damage thereto, and the threads which are to be used in the reweaving process to be hereinafter described, may be rewoven without damage thereto.

Where the fabric is waxed, the hardened wax will make each thread quite stiff, so that where the warp threads are being removed, the filler threads which lie under a warp thread may be bent backwards, and the filler threads which are over the warp threads may be bent forward. This procedure will make it easy to determine the count or formula, and the procedure as to determining the formula of the warp threads is also repeated as to the filler threads.

To the foregoing objects and others which may hereinafter appear, the invention consists of the novel method as will be more specifically referred to and illustrated in the accompanying drawings, but it is to be understood that changes, variations and modifications may be resorted to which fall within the scope of the invention as claimed.

In the drawings:

Figure 1 is a plan view of a fragmentary portion of a damaged fabric with the strands or threads of yarn spread apart for convenience of illustration.

Figure 2 is a plan view of a fragmentary portion of the fabric partly in section showing the first step in the reweaving process.

Figure 3 is a view similar to Figure 2 but showing a pair of warp threads rewoven into the fabric.

Figure 4 is a fragmentary plan view of the fabric showing the second step in the reweaving which includes the weaving of the weft or filler threads in the fabric.

Figure 5 is a plan view of the fragmentary portion of the fabric with the weft or filler and warp threads rewoven into the fabric.

Figure 6 is a plan view of the finished reweaving wherein the opposite ends of the inserted or rewoven strands are cut off.

Figure 7 is a diagrammatic view showing a fabric showing in dot and dash lines waxed portions thereof.

Figure 8 is a fragmentary sectional view of a strand used in a fabric wherein the fibers forming the strand are relatively loose.

Figure 9 is a view similar to Figure 8 but showing the loosely twisted strand coated with wax or paraffin to hold the fibers together.

Figure 10 is a perspective view of a rewoven fabric, shown diagrammatically wherein the rewoven strands are coated with wax or paraffin and the manner in which the wax or paraffin is removed from the rewoven strands.

Figure 11 is a sectional view taken substantially on the line 11-11 of Figure 2.

Figure 12 is a fragmentary plan view of a series of strands or threads showing the manner in which the rewoven strand or thread is positioned

with respect to the remaining strands or threads in the fabric.

Figure 13 is a diagrammatic view of a damaged fabric wherein certain of the warp and filler or weft threads are worn but not completely severed.

Figure 14 is a sectional view taken on the line 14-14 showing the first step in reweaving a new thread in the worn area of the fabric shown in Figure 13.

Figure 15 is a view similar to Figure 14 but showing the inserted or new thread rewoven into the fabric.

Figure 16 is a view similar to Figures 14 and 15 but showing the opposite ends of the inserted or rewoven strand cut off to provide a finished article.

Figure 17 is a fragmentary plan view of the fabric shown in Figure 13 and showing the manner in which the outer ends of the inserted strands or threads are staggered and cut off in order to eliminate any definite lines at the marginal edges of the inserted strands or threads.

In the reweaving of a damaged fabric where the damage consists of strands which are worn thin or is in the form of a hole in the fabric, the first step in connection with the repair of the damaged area is to initially determine the exact weave of the particular fabric. The word "formula" as herein used relates to the specific weave of the warp and weft or filler strands making up the fabric. In the example of a fabric shown in the drawings, the fabric is made up of warp and filler or weft threads or strands which are woven together by what is known as a tabby weave, wherein the filler or weft threads are woven alternately over and under the warp and weft threads. It will be understood that the weaving process hereinafter described may be used with any weave, so that when the inserted threads are rewoven according to the specific weave, the inserted threads will substantially vanish or be imperceptible. In certain fabrics where the weave is fairly loose or where the strands of the yarn are fairly thick or large, the weave formula can be easily and quickly determined by a visual inspection of the fabric.

Another method of determining the particular weave formula of the fabric is to inspect the fabric under a magnifying glass, and if necessary, pull out certain of the strands adjacent an edge of the fabric while under a magnifying glass, so as to determine the particular weave formula of the fabric.

Where the fabrics are very closely woven, and even packed or battened so tightly that one warp thread is bent over or under the next warp thread in such a manner that it is impossible to unravel these threads in a uniform manner, and since one thread will tend to bend over the other, the count is confused, that is, the number of warp and filler threads may be confused, and the specific weave formula may also be confused. Furthermore, the threads may be so loosely twisted that they tend to separate or the fibers intermingle and in addition, the threads tend to disintegrate when separated. The use of a magnifying glass facilitates the determination of the weave formula as it enlarges the fibers, but with certain fabrics the threads appear as a mass of fibers, so that no distinction is possible between each thread. This may be overcome by waxing the threads to break down the weave so that the weave may be determined and a reweaving formula may be prepared. To accomplish this, a small section of the fabric is obtained, a pin fas-

tened to the upper right corner identifying the face of the fabric and the direction of the warp and the filler threads. The fabric is then dipped in molten wax. When the wax is congealed, some filler threads at the top and the warp threads at the left are removed. The overhanging thread ends are placed stiffly erect and are separated easily because each is waxed. Since the waxed threads tend to stand stiffly apart, they are easily counted.

For example, as a filler thread is removed from left to right, raising it gradually through the waxed warp threads that are standing erect, the warp threads that go over this first filler thread are bent forwardly, and the warp threads underneath the filler thread that is being removed are bent backwards as the count is secured. The counted strands are then out of the way. After this, the filler thread is removed and the bent warp threads are straightened back to their original position. The wax will again hold them stiffly erect and the count or weave of the next filler thread over and under the warp threads may be obtained, as this next filler thread is removed. When the repeat of the weave is reached, the correct reweaving procedure, both warp and fillerwise, may be formulated on a reweaver's formula chart. It sometimes is necessary to restore only the warp threads or only the filler threads. The "Reweaving Formula" is complete both ways, because the reweaver must consider the formula from both warp and filler direction since the threads are anchored in a completed fabric.

The specific weave of the fabric can be determined by other methods, it being understood that the exact weave of the fabric is to be determined before commencing the reweaving operation.

After determining the specific weave formula of the fabric, the next step in this process is to find portions of the fabric wherein identical warp and filler threads may be removed from the fabric for use in reweaving the damaged area of the fabric.

Where the fabric is made up as a garment, the threads or strands to be rewoven into the damaged area may be taken from concealed portions of the garment, so that the garment will not be injured by the removal of such threads or strands. The threads or strands which are to be rewoven into the fabric, so as to reweave or reconstruct the weave of the fabric within the damaged area, are preferably of a length about one and one-half inches longer than either the length or width of the damaged area. It is preferable at the time the threads or strands are removed from the fabric at some inconspicuous point in the fabric that such threads or strands be laid aside in the same position as the position they assume in the original fabric. In other words, the warp threads or strands are laid lengthwise, and the filler or weft threads or strands are laid crosswise and at one side of the warp threads or strands. In this manner the person performing the reweaving operation will not mistakenly insert filler or weft threads or strands in place of the warp threads or strands.

Having removed the warp and filler or weft threads from an inconspicuous portion of the fabric, which in the drawing is generally designated as 20, the fabric is turned sidewise so that the warp of the fabric is in a substantially horizontal position. The fabric adjacent the damaged area, designated 21, is pinned to a weighted

and fabric-covered block with an edge of the fabric loose and extending from the block in the direction of the worker. A reweaving needle, generally designated as 22, is woven over and under the filler threads and projected lengthwise through a warp thread inwardly from an end of the latter, as shown in Figure 2, and is also woven over and under the filler strands or threads 23 of the fabric 20 which are accumulated on the shank or stem of the needle 22. The needle 22 is provided with a forward pointed end 25 and a hook 26.

In order to facilitate the obtaining of the warp and filler threads from a selected portion of the garment or fabric, a picker pin 28 is provided. The picker 28 is secured at its rear end in a handle 29 within which the stem 24 of the needle 22 is also secured. The pin or picker 28 extends from the handle 29 in a divergent relation with respect to the stem or shank 24 of the needle 22, as shown in Figure 11. The pin or operator 28 is substantially shorter in length than the length of the needle 22. The needle 22 at its forward end is provided with a pivoted latch or guard 30 which is adapted to engage the hook 26 at the time the needle 22 is withdrawn from the fabric. At the time the needle 22 is initially started through the fabric, the needle 22 is projected in and out of warp thread 27, as shown at 31. When the needle 22 is woven over and under the filler threads from a point at one side of the damaged area 21, the needle 22 is again projected, as shown at 32, lengthwise through the aligned warp strand 27 from the inner free end thereof and is woven over and under the filler strands on the opposite side of the hole 21.

A new warp strand or thread 33 is then engaged and looped onto the hook 26 of the needle 22 and the latch moved to a closed position. The new warp strand 33 is then rewoven over and under the filler strands 23 by withdrawing the needle 22 from the fabric and weaving the new warp strand 33 in place. The opposite ends of the rewoven warp strand 33 may terminate within a pierced portion of the warp strand 27. This operation of inserting the new warp strands is continued until the damaged area has been covered by the new warp strands 33.

After the initial step hereinbefore described has been completed, that is, after the new warp strands 33 have been rewoven into the fabric 20 and the rewoven strands anchored as at 31 and 32, the fabric is turned at right angles so as to position the warp strands 27 vertically and the weft or filler strands horizontally. The manner in which the new weft or filler strands 34 are reweoven into the fabric 20 is the same in which the warp strands 33 were rewoven into the fabric. In other words, the new filler strands are woven over and under the original, as well as the new warp strands, and are also projected into aligned filler strands.

The new filler or weft strands 34 adjacent the outer portions thereof are adapted to be extended lengthwise through the fibers forming the weft or filler strands 23, as shown at 35 and 36. The inserted weft or filler strands, when rewoven into the fabric 20, will be as shown in Figure 5. After the weft or filler strands have been rewoven into the fabric 20, the damaged area 21 which is here shown as being an area having an irregular outline will substantially disappear.

The opposite or free ends of the warp and filler or weft strands, if projecting from the fabric, are then rewoven into the fabric and pro-

jected into the aligning strands on the under-side of the fabric, to thereby provide additional anchoring strength, and at this time, the fabric which has been completely rewoven in the damaged area 21 thereof and at points laterally of the damaged area will be as shown in Figure 6.

The warp and filler or weft strands shown in Figures 1 to 6, inclusive, have been shown with the respective strands spaced apart in exaggerated form with the inserted warp and filler strands across the hole 21 offset from the fabric strands in order to clearly define the inserted warp and filler strands 33 and 34, respectively. In actual practice, however, the inserted warp and filler strands will be in axial alignment and can only be seen by placing the rewoven or reconstructed fabric before a strong light at which time the extended ends of the inserted or rewoven warp and filler strands will appear as deep shadows in the fabric.

Where the fabric, as shown by the numeral 31 in Figure 7, is formed of loosely twisted strands, it is difficult to remove the desired strands, both warp and filler or weft strands, from the fabric without pulling the strands apart. In order, therefore, to provide a means whereby the warp and filler strands may be taken from an inconspicuous portion of the fabric without damaging the removed strands, the fabric 31 is waxed as shown by the dot and dash lines 38 and 39. This procedure may also be used to determine the weave of certain fabrics. After the fabric 31 has been waxed or coated with paraffin which is adapted to substantially impregnate each strand, the warp strands or threads 40 are pulled out and then the weft or filler strands 41 are removed from the fabric 31. The waxed or coated strands 40 and 41 are then rewoven into the fabric 37 after the manner shown in Figures 2 to 6 inclusive. The waxed strands 40 and 41 when rewoven into the fabric 37 are then subjected to a steam blast from a steam nozzle 42 as shown in Figure 10 with a blotter or other absorbent means on the underside of the fabric.

The hot steam will melt and remove the wax from the coated strands so that the inserted warp and filler or weft strands 40 and 41, respectively, will be in their original uncoated condition. A blotter or other absorbent element may be positioned beneath the fabric to thereby absorb the melted wax. In Figure 8, there is shown in enlarged section a loosely twisted strand 40 with the fibers extending from the strand, whereas in Figure 9, the strand 40 is shown as being coated by wax 38.

In order to provide for reweaving of the warp and weft strands, so that after the reweaving operation has been completed, the rewoven strands cannot be detected, the rewoven strands shown by the numeral 43 in Figure 12 are so positioned in their inserted relation with respect to the warp or weft strands 44 that the twist of the fibers, shown by the numeral 45, will be in the same direction as the twist of the fibers 46 in the fabric strands 44. After the reweaving operation has been completed, as shown in Figure 6 or in Figure 10, the repaired fabric is pressed in the usual manner so as to flatten the interwoven new threads. This latter operation will eliminate any detection of the reweaving operation except under very close examination involving the use of light at one side of the fabric.

In Figures 13 to 17, inclusive, there is disclosed a modified form of reweaving process, wherein

the fabric 47 has a worn area 48 designated by the dot and dash line 49. The warp strands 50 are initially lifted at a point spaced from the worn area 48 by means of the lifting pin 28, shown in Figure 11. The pulled or lifted portion of the warp strand 50 is then cut off, as shown at 51, and a short length of the cut strand 50 is then withdrawn or unwoven from the filler or weft strands 52. The needle 22 is then projected through the loosened end 53 of the warp strand 50 at several spaced points, as shown at 54, and a new or unworn strand 55 is engaged with the hook 26 of the needle 22. The end of the new strand 55 is then pulled through the pierced portions 54 of the end 53 thereby locking or tying one end of the new strand 55 directly to the end 53 of the warp strand 50. The warp strand 50 is then cut off as at 56 at a point on the opposite side of the worn area 48.

The end 57 which is opposite from the end 53 is then pulled endwise, so as to pull out the now completely cut warp strand 50 from the fabric 47. As the worn warp strand 50 is pulled out, the new or unworn strand 55 is rewoven over and under the filler or weft strands 52, and the new strand 55 will then assume the position shown in Figure 15 with the opposite ends 58 and 59 thereof extending from one side of the fabric 47. The warp strands which are to be removed from the fabric 48 at their opposite ends are preferably cut off in staggered relation, as shown in Figure 17, so that there will not be any definite line of these severed warp threads remaining in the fabric 47.

The filler or weft threads are rewoven in the same manner, as shown in Figures 14 and 15, being rewoven over and under the newly inserted warp threads 55. After the warp and weft or filler threads 55 and 60, respectively, have been rewoven into the fabric 47, the opposite or free ends thereof are then rewoven into the fabric 47 in the manner shown in Figures 2 and 11. That is, the needle 22 is extended over and under the filler or weft threads from a point beyond which the original warp threads 50 were cut and then the free ends 58 and 59 of the warp threads 55 are pulled over and under the original weft or filler threads 52. When this latter reweaving operation of the free ends of the inserted warp and filler or weft threads 55 and 60 has been completed, the ends of these inserted threads will appear as shown in Figure 17. The opposite ends 58 and 59 of the inserted or rewoven warp threads 55 will extend beyond the point at which the original warp threads 50 were cut off.

Preferably the ends of the inserted warp and weft or filler threads are alternately longer and shorter, so as to provide a staggered joining line which in the completed reweaving operation will not be discernible.

The method of reweaving a fabric as hereinbefore described has been placed in actual use and by reason of the anchoring of the opposite ends of the inserted strands, the inserted strands are firmly held within the original fabric and will not readily pull out under normal or even hard usage of a garment.

As hereinbefore stated, it is important in performing the reweaving operation that identical warp and filler or weft threads be provided for the reweaving or reconstructing operation. Inasmuch as most garments are constructed with extending edges in various portions of the garment, these inserted strands can readily be

found and removed without detection from the garment. It is also important that the exact weave of the fabric be found. Under certain conditions the weave may be determined by a visual inspection or an inspection under a magnifying glass. Under other conditions it is necessary to wax a portion of the fabric and then loosen the waxed strands which are stiffened by the wax. When the wax strands are loosened or spread apart a slight distance, the weave can be readily determined, or the strands are removed until a repeat of the weave occurs.

The method of reweaving a fabric as hereinbefore described has also been found to be more satisfactory from the standpoint of the owner of the garment in that the exact point of the repair of reweaving of the fabric cannot be determined except by a very close inspection of the garment. This method of reweaving or reconstructing the fabric at and about a damaged area is much more satisfactory to the owner of the garment or fabric, as the rewoven fabric will wear in the same degree as the original fabric, and will not pull out as is the case where a patch is inserted within a hole.

What we claim is:

1. The method of reweaving a damaged fabric which includes initially reweaving a plurality of strands into the fabric on opposite sides of the damaged area, said strands being disposed in alignment with correlated strands of said fabric, reweaving a plurality of strands into the fabric at right angles to said first strands, said second strands being rewoven into opposed portions of the fabric and also into said first strands in a weave identical with the weave of said fabric, said strands being identical as to diameter, fiber content and fiber arrangement with correlated strands of said fabric, and anchoring the opposite ends of all of said strands relative to selected strands of said fabric.

2. The method of reweaving a damaged fabric which includes initially reweaving a plurality of strands into the fabric on opposite sides of the damaged area, reweaving a plurality of strands into the fabric at right angles to said first strands, said second strands being woven into opposed portions of the fabric and also into said first strands, and threading opposite end portions of said first mentioned and second mentioned strands through selected strands of said fabric to thereby anchor the first and second mentioned strands relative to the fabric.

3. The method of reweaving a damaged fabric which includes initially reweaving warp strands into the fabric and across the damaged portion thereof with the warp strands extending a substantial distance from opposite sides of the damaged portion, and reweaving filler or weft strands through said warp strands and into the fabric a substantial distance from the remaining edges of the damaged portion said strands being disposed in alignment with correlated strands of said fabric, and said strands being identical as to diameter, fiber content and fiber arrangement with correlated strands of said fabric.

4. The method of reweaving a fabric having a thin or worn area which includes initially progressively cutting the warp strands of the fabric at opposed points outwardly of the worn area, 5 raising an end of a worn warp strand, securing an end of a new warp strand onto the raised end of a worn portion of the warp strand, withdrawing the worn warp strand endwise to remove the latter and reweave the new warp strand in the place of the worn warp strand, progressively cutting the filler or weft strands of the fabric outwardly of the worn area, raising an end of a worn filler or weft strand, securing an end of a new filler strand onto the raised end of a portion of a 10 worn filler or weft strand, withdrawing the worn portion of the filler or weft strand endwise to remove the latter and reweaving the new filler or weft strand in the place of the worn filler or weft strand.

5. The method of reweaving the worn area of a fabric which includes initially removing the worn portion of the warp strands from the fabric, reweaving new warp strands in the place of the worn portion of the warp strands, removing the 15 worn portion of the filler or weft strands from the fabric, reweaving new filler or weft strands in place of the worn portion of the filler or weft strands, and anchoring the inserted warp and filler strands with the warp and filler strands of the fabric.

6. The method of reweaving the worn area of a fabric which includes initially removing the worn portion of the warp strands from the fabric, reweaving new warp strands in the place of the 20 worn portion of the warp strands, removing the worn portion of the filler or weft strands from the fabric, and reweaving new filler or weft strands in place of the worn portion of the filler or weft strands, the reweaving warp and filler or weft strands having a length greater than the length 25 of the removed warp and filler or weft strands, and finally reweaving and anchoring the extended ends of the warp and filler or weft strands into the fabric to thereby provide for an overlapping 30 of the rewoven strands with respect to the warp and filler or weft strands of the fabric.

7. The method of repairing a hole in a fabric which includes reweaving individual warp and weft or filler strands across the hole and into the 35 fabric outwardly of the hole and interlocking the inserted strands with the fabric strands said strands being disposed in alignment with correlated strands of said fabric, and said strands being identical as to diameter, fiber content and fiber arrangement with correlated strands of said fabric.

8. The method of reweaving a hole in a fabric which includes reweaving warp and filler or weft strands into the fabric outwardly of the hole and 40 into each other, anchoring the ends of the inserted warp strands by piercing adjacent fabric warp strands, and anchoring the ends of the inserted filler or weft strands by piercing adjacent fabric weft strands.
